Primary Examiner — Barbara Fox*Assistant Examiner* — Dana K Weiland(74) *Attorney, Agent, or Firm* — Birch, Stewart, Kolasch & Birch, LLP(57) **CLAIM**

The ornamental design for a television receiver, as shown and described.

DESCRIPTION

1. Television receiver

1.1 is a perspective view of the television receiver showing the new design;

1.2 is the front view thereof;

1.3 is the back view thereof;

1.4 is the left side view thereof, where the right side view is a mirror image;

1.5 is the top view thereof;

1.6 is the bottom view thereof; and

1.7 is another front view showing the television receiver in use.

(Continued)

The broken lines shown in the figures depict portions of the television receiver that form no part of the claimed design.
